CLAIM

The ornamental design for a jewelry setting, as shown and described.

DESCRIPTION

FIG. 1 is a top plan view of a jewelry setting;

FIG. 2 is a first side view thereof;

FIG. 3 is a second side view thereof;

FIG. 4 is a bottom plan view thereof;

FIG. 5 is a first top perspective view thereof;

FIG. 6 is a second top perspective view thereof; and,

FIG. 7 is a bottom perspective view thereof.

The broken line showing of parts of the drawings is included for the purpose of illustrating use and environment and forms no part of the claimed design.
